Des. 222,427
Patented Oct. 26, 1971

222,427

DOOR HANDLE OR SIMILAR ARTICLE

William G. Deuring, Jr., Pittsfield, Mass.,
assignor to General Electric Company

Filed Jan. 19, 1970, Ser. No. 20,962

Term of patent 14 years

Int. Cl. D8—07

U.S. Cl. D8—161

Fig. 2.

Fig. 1.

Fig. 3.

Fig. 5.

Fig. 4.

FIG. 1 is a front elevation view of a door handle or similar article showing my new design, the opposite side thereof being substantially a mirror image of the view shown in FIG. 1;

FIG. 2 is an end elevation view of the uppermost end of the handle depicted in FIG. 1;

FIG. 3 is a side elevation view of a door handle as would be seen from the right side of the handle depicted in FIG. 1;

FIG. 4 is an end elevation view of the bottom end of the handle depicted in FIG. 1; and

FIG. 5 is a perspective view of the handle depicted in FIGS. 1-4.

I claim:

The ornamental design for a door handle or similar article, as shown and described.
